UNITED STATES PATENT OFFICE.

RANDAL E. TALLEY, OF IRWIN, PENNSYLVANIA, ASSIGNOR TO GEORGE J. HAGAN COMPANY, A CORPORATION OF PENNSYLVANIA.

ELECTRIC FURNACE.

Application filed July 19, 1923. Serial No. 652,467.

To all whom it may concern:

Be it known that I, RANDAL E. TALLEY, a citizen of the United States, and a resident of Irwin, in the county of Westmoreland and the State of Pennsylvania, have made a new and useful Invention in Electric Furnaces, of which the following is a specification.

This invention relates to electric furnaces and more particularly to electric vitreous enameling furnaces such as are used, for example, in the manufacture of kitchen ware and the like.

In furnaces of the latter type the amount of heat lost through the door is many times higher than is the case with furnaces used for ordinary heating purposes due to the fact that in an enameling furnace the door must be frequently opened to permit removal of the finished product and the placing of a fresh charge. In running more than twenty charges of ware per hour the furnace door must be opened more than forty times and if as high as thirty charges per hour are run the door must be opened every minute.

In any electric furnace the ratio of heat lost by radiation through the door structure to that lost through the furnace walls is about 3 to 1.

An object of my invention is to provide a furnace with heating elements so positioned as to compensate for the large amount of heat lost through the door.

A further object is to provide a vitreous enameling furnace having a door compensating winding so placed in relation to the door as to supply additional heat at the point of greatest heat loss.

My invention is shown as applied to a double end furnace of the resistance type but it is obviously applicable to other types of electric furnaces.

In the drawings, showing one embodiment of my invention, Figure 1 is a plan view partly in horizontal section. Fig. 2 is a vertical cross section on the line 2—2 of Fig. 1, looking in the direction of the arrows. Fig. 3 is a side elevation partly in vertical section taken on the line 3—3 of Fig. 1, looking in the direction of the arrows.

As shown, my invention is applied to an

ordinary electric furnace having the usual hearth 1, side walls 2 and 3 and an arch 4, all of which may be of any desired construction. Supported along the walls of the furnace are the usual heating elements 5. On the front wall 6 is the usual door 7 shown, in this case, as suspended on supporting chains 8 running over sheaves 9. The door may be of any desired type and operated by any suitable mechanism, as this forms no part of my present invention.

In order to compensate for the large amount of heat which is lost through the furnace door as above described I provide an additional heating element or compensating winding 10 located on the front wall of the furnace and, preferably, directly beneath the door opening.

I have found this to be the most advantageous and efficient way of compensating for the heat lost through the door as such an element, so placed, provides additional heat immediately below the point of the greatest heat loss resulting in a more efficient furnace and a more uniform temperature in the heating chamber.

Without such a compensating element that part of the heating chamber adjacent the door would be cooler than the rest of the chamber. This would result in an unevenly heated furnace, thereby greatly reducing the operating efficiency thereof.

By providing my compensating element a source of heat is provided directly beneath the otherwise cool part of the furnace, and heat issuing therefrom counteracts the loss through the door structure and provides a uniformly heated furnace, of high capacity and efficiency.

I claim:

1. An electric furnace having heating elements along the walls thereof, a door and a compensating heating element so positioned as to compensate for heat lost through said door.

2. An electric furnace having heating elements along the walls thereof, a door in one vertical wall and a compensating heating element so positioned on said wall as to compensate for heat lost through said door.

3. An electric furnace having heating elements along the walls thereof, a door in one

vertical wall and a compensating heating positioned on said wall beneath said door element so positioned on said wall adjacent as to compensate for heat lost through said said door as to compensate for heat lost door. 10 through said door.

5 4. An electric furnace having heating elements along the walls thereof, a door in one wall and a compensating heating element so

In testimony whereof, I have hereunto subscribed my name this 16th day of July, 1923.

RANDAL E. TALLEY.
